UNITED STATES PATENT OFFICE.

JONATHAN R. HAMILTON, OF KINGSTON, MINNESOTA, ASSIGNOR OF
ONE-HALF TO WALTER DIXON, OF KIMBALL, MINNESOTA.

BATH APPARATUS.

SPECIFICATION forming part of Letters Patent No. 758,207, dated April 26, 1904.

Application filed April 10, 1903. Serial No. 151,943. (No model.)

To all whom it may concern:

Be it known that I, JONATHAN R. HAMILTON, a citizen of the United States, residing at Kingston, in the county of Meeker and State of Minnesota, have invented certain new and useful Improvements in Bath Apparatus, of which the following is a specification.

My invention relates to improvements in bath apparatus, its object being particularly to provide an improved combination sitz, foot, vapor, and hot-air bath.

To this end my invention consists in the features of construction and combination hereinafter particularly described and claimed.

15 In the accompanying drawings, forming part of this specification, Figure 1 is a side elevation of my improved apparatus, partly in section. Fig. 2 is a top view of my improved apparatus. Fig. 3 is a top view of 20 the seat used in taking a hot-air bath, and Fig. 4 is a top view of the lamp-receptacle forming part of the apparatus.

In the drawings, A and B represent telescoping cylinders. The top 2 of the outside cylinder A is provided with a central opening 3, through which the head of the person taking the bath passes. The size of the opening is determined by the slidably-supported strips 4, the inner curved ends of which form opposite 30 sides of the opening. The cylinder A is supported by cables 5, connected to eyes 6, carried by the cylinder and terminating in a cable 7, passing over a sheave 8. Suitable guide-rods 9 for the cylinder are provided, said 35 guide-rods being secured at their lower ends in brackets 10, carried by the lower cylinder and slidably extending through brackets 11, carried by the upper cylinder.

Arranged within the lower cylinder B is an 40 open-top receptacle C. Supported inside the receptacle upon an arm 12 is a lamp 13. Working in connection with the lamp 13 is a slide 14, having an actuating-handle 15 extending through the side wall of the receptacle and the adjacent side wall of the cylinder B. Having hinge-support 16 upon the

side wall of the receptacle above the lamp is a plate 17. The receptacle C is formed with openings 18 in its wall to permit of circulation of air through the receptacle.

To adapt the apparatus for use as a vapor-bath, I provide the pan 19, formed with a flange 20 at its upper edge to rest upon the edge of the receptacle C. Adapted to be used in connection with said pan is a seat 21, 55 formed with a central opening 22 and having secured to its under side outwardly-extending strips 23, adapted to rest upon the edge of the pan, as shown in Fig. 1. Thus when the seat 21 is in position the vapor may pass 60 from the pan 19 between the outer edge of the seat and the outer edge of the pan. The lower cylinder B is provided with a suitable drain-cock 24. The opening 22 in the seat 21 is normally closed by a cover 25. When it 65 is desired to use the apparatus for a hot-air bath, the seat 21 is removed and the cover 25 placed in the pan 19 and used as a seat.

As shown in Figs. 1 and 3, the handle 15 is made in two pieces connected by a coupling 70 26. The handle may thus be disconnected to allow removal of the receptacle C and its contained parts.

The hinged plate 17 may be turned over the lamp, as shown in Fig. 1, to spread the 75 flame, and the plate may also be used to hold sulfur in taking a sulfur-bath.

Having now described my invention, what I claim as new, and desire to secure by Letters Patent, is—

1. In a bath apparatus of the class described, the combination with two telescoping cylinders, the upper cylinder being formed with a neck-opening, of a receptacle arranged within said cylinder, a pan closing the top of said receptacle, and heating means arranged within said receptacle.

2. In a bath apparatus of the class described, the combination with two telescoping cylinders, the top of the upper cylinder being 90 formed with a neck-opening, of a receptacle within said cylinder, a water-pan removably

supported in the top of said receptacle, and heating means supported in said receptacle below said pan.

3. In a bath apparatus of the class described, 5 an open top, closed bottom, receptacle, a water-pan constructed to fit in the top of said re-ceptacle and extending downwardly therein, heating means supported in said receptacle

underneath said pan, and a seat removably supported in the top of said pan.

In testimony whereof I affix my signature in presence of two witnesses.

JONATHAN R. HAMILTON.
